DESIGN FOR A PROTECTIVE TRANSPARENT HAT COVERING

Louis Royak, New York, N. Y.

Application February 7, 1939, Serial No. 82,839

Term of patent 14 years

To all whom it may concern:

Be it known that I, Louis Royak, a citizen of the United States of America, residing in New York city, in the Borough of Manhattan, county and State of New York, have invented a new, original, and ornamental Design for a Protective Transparent Hat Covering, of which the following is a specification, reference being had to the accompanying drawing, forming part thereof, wherein

Figure 1 is a side view of a protective transparent hat covering showing my new design.

Figure 2 is a bottom plan view of the protective transparent hat covering.

The opposite side of the hat covering is the same as Fig. 1 except for the lacing closure.

I claim:

The ornamental design for a protective transparent hat covering, substantially as shown and described.

LOUIS ROYAK.
